(57) **CLAIM**

The ornamental design for a bed frame, as shown and described.

DESCRIPTION

Cross reference is made to U.S. patent application Ser. No. 29/436,401 entitled "Side Rail for a Bed" by Richard H. Heimbrock, which was filed on Nov. 5, 2012 and is hereby incorporated herein by reference.

FIG. 1 is a perspective view of a foot end of a bed frame showing our new design;

FIG. 2 is an elevation view of the foot end of the bed frame of FIG. 1;

FIG. 3 is an elevation view of a head end of the bed frame of FIG. 1;

FIG. 4 is a top plan view of the bed frame of FIG. 1;

FIG. 5 is a cross-sectional view of the bed frame of FIG. 1 taken along line 5-5 in FIG. 4;

FIG. 6 is a cross-sectional view of the bed frame of FIG. 1 taken along line 6-6 in FIG. 4;

FIG. 7 is a cross-sectional view of the bed frame of FIG. 1 taken along line 7-7 in FIG. 4;

FIG. 8 is a first side elevation view of the bed frame of FIG. 1;

FIG. 9 is a second side elevation view of the bed frame of FIG. 1;

FIG. 10 is a bottom plan view of the bed frame of FIG. 1;

FIG. 11 is a perspective view of the head end of the bed frame of FIG. 1; and,

FIG. 12 is a cross-sectional view of the bed frame of FIG. 1 taken along line 11-11 in FIG. 4.

The broken lines shown in the figures depict environmental subject matter and form no part of the claimed design.

1 Claim, 12 Drawing Sheets
